UNITED STATES PATENT OFFICE.

JOUEL M. SHACKELFORD AND TRUMAN ALEXANDER, OF ASHLAND, KENTUCKY.

ARTIFICIAL HAND.

1,004,482.

Specification of Letters Patent. Patented Sept. 26, 1911.

Application filed December 30, 1910. Serial No. 600,075.

To all whom it may concern:

Be it known that we, JOUEL M. SHACKELFORD and TRUMAN ALEXANDER, citizens of the United States, residing at Ashland, in the county of Boyd and State of Kentucky, have invented new and useful Improvements in Artificial Hands, of which the following is a specification.

The present invention is an improvement in artificial hands, and its object, stated broadly, comprehends the production of a device of that type so constructed as to provide for flexion of the fingers and thumb as nearly as possible in the same manner as the corresponding parts of a natural hand, for obtaining such flexion by a slight movement of the wrist or arm of the wearer, for locking the fingers and thumb in adjusted position, so as to relieve the strain upon the wrist and arm, and for permitting both a turning movement and an up and down movement of the hand.

A structural embodiment of the invention is illustrated in the accompanying drawings, wherein—

Figures 1 and 2 are, respectively, a plan view and a side elevation of the improved hand, both views having parts thereof broken away; Fig. 3 is a transverse section taken on the line 3—3 of Fig. 2; Figs. 4 and 5 are, respectively, an inner side elevation and a plan view of one of the fingers; Fig. 6 is a perspective view of the top or first joint of a finger; Fig. 7 is a transverse sectional view taken on the line 7—7 of Fig. 4; Fig. 8 is a perspective view of the universal joint connection between the body of the hand and the arm of the wearer, the parts thereof being shown as separated; Fig. 9 is a detail longitudinal sectional view of the gear train which operates the finger-actuating shaft; Fig. 10 is a side elevation, with parts in section, of a modified form of hand; and Fig. 11 is a transverse section taken on the line 11—11 of Fig. 10.

As shown in said drawings, the hand comprises the body portion, generally indicated by the numeral 1, fingers 2, 3, 4 and 5, and thumb 6, the first-mentioned part being designed for connection to a sleeve 7 through the intermediary of the wrist-plates 8 and 9. Sleeve 7 may be constructed in any preferred manner and from any suitable material, and is adapted to be fitted tightly on the stump 55 of the fore-arm of the wearer. Each finger consists of three sections 10, 11 and 12 that

correspond to and have the same relative proportions as the first, second and third joints of a natural finger, while the thumb, in like manner, is composed of the two sections 13 and 14. The sections of each finger are provided at their inner ends with rounded tongues 10', 11' and 12', the tongues 10' and 11' fitting in the rounded forks 11² and 12² with which the outer ends of the sections 11 and 12 are provided and being pivotally connected to said forks by pivot pins 15 and 16. Similarly, the thumb sections 13 and 14 are provided with tongues 13' and 14', the former of which fits in the fork 14² in the outer end of the section 14 and is connected to the same by the pivot pin 17. For convenience, the sections of the several fingers, as well as those of the thumb, are formed of substantially counterpart halves, 75 which are arranged with their inner longitudinal faces in mutual contact, (see Figs. 4 to 7).

Means is provided for operating the fingers and thumb simultaneously, and such means is itself intended to be actuated by a twist or turn of the wrist of the wearer. In the construction illustrated, the fingers are mounted on a square shaft 18 that passes through correspondingly shaped openings 85 formed through the tongues 12', said shaft being arranged within and transversely of the hollow body portion 1 and having its reduced ends journaled in screw plugs 19 removably fitted in the side walls of said body 90 portion. Rotation or rocking of shaft 18 will, therefore, directly affect the finger sections 12. Each section 12 is rotatable with respect to a stationary anchor 20 which is provided with an enlarged head 20' that is 95 inserted between the halves of said section and is pivoted or swivelly connected to a flanged collar 21 formed on the inner face of one of said halves, as shown in Fig. 7, the anchor itself being securely fastened in the 100 body portion 1 by a screw 22, or the like, passed through its eye 20². Collar 21 is so positioned as to permit the shaft 18 to pass through it, being provided for that purpose with a square axial opening. The free end 10 of each tongue 12' is slotted or recessed, as at 12³, to receive the stem of the corresponding anchor, thus permitting the desired movement of said section.

To produce the requisite movement of the 11 sections 10 and 11 at the same time as that of the sections 12, the latter are so connect-

ed with the second sections 11 as to transmit their movement thereto, and said sections 11 are connected, in turn, with the sections 10 for the same purpose. Pairs of crossed links 23-24 and 25-26 may be advantageously utilized for such connections, the links 23 and 24 being disposed between the halves of the sections 12 and pivoted at their inner ends to the corresponding anchor head 20' at opposite sides of the shaft opening, while the outer ends of these links extend between the halves of the tongue 11' and are pivoted at opposite sides of the pin 16, (see Fig. 4). There is also secured between the halves of each section 12 a second anchor 27 having an enlarged apertured head 27' through which pin 16 passes, and to this head, on opposite sides of said pin, are pivoted the inner ends of the pair of links 25 and 26, the outer ends 20 of these links being inserted between the halves of the tongue 10' of the corresponding section 10, as shown in Fig. 6, and pivoted thereto on opposite sides of the pin 15. The foregoing arrangement is such, therefore, that when shaft 18 is rotated in one direction, the four fingers will assume their doubled position shown in dotted lines in Fig. 2, and, on rotation of said shaft in the other direction, will move into their extended position shown in full lines in that figure.

In order to obtain a corresponding synchronous movement of the thumb, the latter is connected with the index finger 2, preferably through the medium of a single link 28, as hereinafter described. The second or inner section 14 of the thumb is pivotally mounted on a cross-pin 29 which extends through the tongue 14' of that section and is fitted at its ends in seats formed in the side walls of a slot 30 leading into the interior of the body portion 1. To said tongue there is also connected a link 31 that is disposed between the tongue halves and is fastened centrally to the same by a pin 32, one end of said link being connected to pin 29 and the other end to the inner end of link 28. Movement of the section 12 of finger 2 will thus entail a movement of section 14, the latter transmitting its movement to the first or outer section 13 by a pair of crossed links 33 and 34, these links being pivoted at their outer ends to tongue 13' on opposite sides of pin 17 and at their inner ends to the head 35' of an anchor 35.

The free end of the stem of anchor 35 is connected to the adjacent reduced terminal of a shaft 36 which is disposed within the interior of the body 1 parallel with shaft 18, plugs 37 similar to the plugs 19 above described being employed as journals for the ends of said shaft. Shaft 36 may likewise be square in cross-section and is connected with shaft 18 by means of gearing, two trains of gears being preferably employed.

Each train comprises three gears 38, 39 and 40, of gradually decreasing size, the gears 38 and 40 being provided with sleeves 38' and 40', which fit on shafts 36 and 18 and are revoluble in openings formed in the pair of plates 41 located on opposite sides of each train, the central gear 39 of each train being mounted on a pin 42 connecting the central portions of the adjacent pair of plates. The largest gear 38 of each train may be, and preferably is, in the form of a segment.

Shaft 36 is driven by means of a direct gear connection with the main operating shaft, which is itself rotated by a twist or turn of the wrist of the wearer, the employment of the increasing trains of gears permitting a complete movement of shaft 18 to be effected by a comparatively slight turn of the wrist. In the form of the invention shown in Figs. 1 to 3, the operating shaft 43 carries a bevel gear 44 which meshes with a smaller gear 45 secured to shaft 36, while the latter shaft, in the modification shown in Fig. 10, carries a worm wheel 46 in mesh with and driven by a worm 47 provided upon the operating shaft 48.

Shaft 43 extends through registering openings in the base 1' of the body portion 1 and the front wrist-plate 9 and carries a two-armed rocker 49 suitably fastened to the under face of gear 44. Base 1' is formed with a pair of diametrically-opposite arcuate slots 50 in which are movable the forward portions of a pair of rods 51. These rods are connected at their front ends to the terminals of the arms of rocker 49, pass through openings 52 in the front wrist-plate 9, and project at their rear ends through similar arcuate slots 54 formed in the rear wrist-plate 8, the rear face of said plate 8 being formed with a pair of transverse parallel channels 55 having concave or dished inner walls, as shown in Fig. 8. The front face of plate 8 is convex and coacts with the concave rear face of plate 9, the latter plate being preferably hollow and having the openings in its rear wall of greater size than those in its front wall. Each rod is encircled by a tension spring 56 located interiorly of plate 9 and projecting at its rear end through the corresponding opening in the rear wall of said plate, so as to bear against the front face of plate 8, the front end of the spring bearing against the inner face of the front wall of plate 9. These springs serve to hold the mutually-adjacent faces of the base 1' and plate 9 in contact, thereby preventing the hand proper from slipping under normal conditions. The rear ends of the rods carry nuts 57 which are received in the channels 55 and are adapted to be tightened against the dished inner walls thereof. Shaft 43 also carries nuts 58 adapted to be tightened against the inner wall of a seat 59 formed in base 1', this seat being inter-

sected by the opening wherein said shaft is disposed. The hand and the front wrist-plate 9 are capable of a slight up and down movement relative to plate 8, the latter plate 5 being secured in any suitable manner to sleeve 7.

In the modified form shown in Fig. 10, a single hollow wrist-plate 8' is employed. This plate is provided with a concave rear 10 wall which coacts with the convex end plate on sleeve 7', said plate and sleeve having a yielding connection through the medium of a pair of bolts 60 encircled by springs 61 whose tension is controlled by means of nuts 15 62 threaded on the rear ends of the bolts. Said bolts pass through alining slots 63 formed in the rear wall of plate 8', this construction permitting an up and down movement of the hand and wrist with respect to 20 sleeve 7'.

In both forms of the invention, it will be understood, therefore, that a turn or twist of the wrist or arm of the wearer will produce rotation of the operating shaft, which 25 latter will, in turn, rotate the shaft 36 through its gear connections therewith, the rotation of shaft 36 being transmitted to shaft 18 by means of the two gear trains. Shaft 18, on being rotated, will move the 30 four fingers and thumb in unison, the movement of the thumb being occasioned by its link connection 28-31 with the index finger 2. During the movements of the fingers and thumb, they will flex or bend, owing to the 35 pairs of crossed links which connect the sections thereof.

Means is provided in the preferred form of the invention for locking the hand as a whole in adjusted position, to relieve the 40 strain upon the arm. Such means comprises, primarily, a rack 64 that is located within the body portion 1 and is pivoted at one end to the inner wall of base 1'. This 45 rack is normally forced by a spring 65 toward the adjacent arm of rocker 49, which arm terminates in a tooth 66 designed to engage the rack teeth. The opposite end of the rack projects outwardly through a bayonet slot 67 in the back of the body portion 1, 50 and said rack is so mounted on its pivot as to enable it to be forced away from tooth 66 and depressed in said slot, whereby it will be held in inoperative position.

In the second or modified form, the shaft 55 48 is loosely mounted in the body portion 1 and its rear end extends loosely into the wrist-plate 8' and carries a ratchet wheel 68 with which a two-armed pawl 69 co-operates, 60 said pawl being pivoted centrally upon a pin 70 set into the front wall of the wrist-plate. To each end of the pawl a pin 71 is connected, these pins projecting laterally outward through openings in the back of the wrist-plate and terminating in heads. The 65 pawl is also formed with a central V-shaped

projection 72 adapted to be engaged by a spring 73. When both teeth 74 on the outer ends of the pawl arms are out of engagement with the ratchet, the hand may be turned freely in either direction without occasioning movement of the thumb and fingers, but when either pin 71 is pressed inwardly, the pawl will be rocked and the adjacent tooth 74 will be forced into engagement with the ratchet so that a turn or twist 75 of the wrist will then result in the fingers being opened or closed, the tooth 74 being held in such engagement by the pressure of spring 73 against the adjacent side edge of the projection 72. To release the pawl, it is 80 only necessary to return it to its normal or inoperative position by pressing the other pin inwardly to a slight extent.

Shaft 48 is journaled at its forward end in a bearing formed in a bar 75 that connects a pair of spaced brackets 76 which are secured within the interior of the body portion 1 and are located upon opposite sides of said shaft, only one of these brackets, however, appearing in Fig. 10. To reduce friction 90 during the movements of the hand and the shaft 48, ball bearings may be employed, as shown in the figure specified.

The sections of both the fingers and the thumb may, if desired, be equipped with 95 bands of rubber or similar material, as indicated by the numeral 77, for the purpose of affording a firmer grip, and a pad 78 may also be applied to the palm of the hand.

We claim as our invention:

1. In an artificial hand, the combination of a body portion; a shaft journaled therein; a series of jointed fingers having their third joints mounted directly on said shaft; means for rotating said shaft to swing said 105 third joints; and connections between each joint of each finger and the succeeding joint of that finger, for flexing said fingers when said shaft is rotated.

2. In an artificial hand, the combination 110 of a body portion; a shaft journaled therein; a series of jointed fingers having their third joints mounted on said shaft; an anchor associated with the third joint of each finger; means for rotating said shaft to swing said 115 third joints; a pair of crossed links pivotally connecting each anchor and the second joint of the corresponding finger; and a pair of crossed links pivotally connecting the second and first joints of each finger.

3. In an artificial hand, the combination 120 of a body portion; a shaft journaled therein; a series of jointed fingers having their third joints mounted on said shaft; means for rotating said shaft to swing said third joints; connections between each joint of each finger and the succeeding joint of that finger for flexing said fingers when said shaft is rotated; a thumb pivotally connected to said 125 body portion; and direct connections be-

ween the index finger and said thumb for operating the latter from the former and for swinging it in unison therewith.

4. In an artificial hand, the combination of a body portion; a shaft journaled therein; a series of jointed fingers having their third joints mounted on said shaft; means for rotating said shaft to swing said third joints; connections between each joint of each finger and the succeeding joint of that finger for flexing said fingers when said shaft is rotated; a jointed thumb having its second joint pivotally connected to said body portion; connections between said second joint and one of the joints of the index finger for swinging the thumb in unison with said index finger; and connections between the second and first joints of said thumb for flexing the latter during its movements.
5. In an artificial hand, the combination of a body portion; a shaft journaled therein; a series of jointed fingers having their third joints mounted on said shaft; means for rotating said shaft to swing said third joints; connections between each joint of each finger and the succeeding joint of that finger for flexing said fingers when said shaft is rotated; a jointed thumb having its second joint pivotally connected to said body portion; a link rigidly secured to said second joint; a link pivoted at one end to the third joint of the index finger and at the other end to the first-named link for swinging the thumb in unison with said index finger; and connections between the second and first joints of said thumb for flexing the latter during its movements.
6. In an artificial hand, the combination of a body portion; a shaft journaled therein; a series of jointed fingers having their third joints mounted on said shaft; an anchor associated with the third joint of each finger; means for rotating said shaft to swing said third joints; a pair of crossed links pivotally connecting each anchor and the second joint of the corresponding finger; a pair of crossed links pivotally connecting the second and first joints of each finger; a jointed thumb having its second joint pivotally connected to said body portion; connections between the second joint of said thumb and one of the joints of the index finger for swinging the thumb in unison with said index finger; and connections between the second and first joints of said thumb for flexing the latter during its movements.

7. In an artificial hand, the combination of a body portion; a shaft journaled therein; a series of jointed fingers having their third joints mounted on said shaft; an anchor associated with the third joint of each finger; means for rotating said shaft to swing said third joints; a pair of crossed links pivotally connecting each anchor and the second joint of the corresponding finger; a pair of

crossed links pivotally connecting the second and first joints of each finger; a jointed thumb having its second joint pivotally connected to said body portion; connections between the second joint of said thumb and one of the joints of the index finger for swinging the thumb in unison with said index finger; and connections between the second and first joints of said thumb for flexing the latter during its movements.

8. In an artificial hand, the combination of a body portion; a shaft journaled therein; a series of jointed fingers having their third joints mounted on said shaft; an anchor associated with the third joint of each finger; means for rotating said shaft to swing said third joints; a pair of crossed links pivotally connecting each anchor and the second joint of the corresponding finger; a pair of crossed links pivotally connecting the second and first joints of each finger; a jointed thumb having its second joint pivotally connected to said body portion; connections between the second joint of said thumb and one of the joints of the index finger for swinging the thumb in unison with said index finger; an anchor associated with the said second joint of said thumb; and a pair of crossed links connecting the last-named anchor and the first joint of said thumb for flexing the latter during its movements.

9. In an artificial hand, the combination of a body portion; a series of jointed fingers and a jointed thumb pivotally connected to said body portion; means for moving said fingers in unison; means for flexing said fingers during their movements; connections between the index finger and the second joint of said thumb for moving the latter in unison with said index finger; and connections between the second and first joints of said thumb for flexing said thumb when the same is moved.

10. In an artificial hand, the combination of a body portion; a series of jointed fingers and a jointed thumb pivotally connected to said body portion; means for moving said fingers in unison; means for flexing said fingers during their movements; a link rigidly connected to the second joint of said thumb; a link pivoted at one end to one joint of the index finger and at the other end to the first-named link for moving said thumb in unison with said index finger; and connections between the second and first joints of said thumb for flexing the latter when the same is moved.

11. In an artificial hand, the combination of a hollow body portion; a pair of parallel shafts journaled therein; means for positively driving one of said shafts; gear connections between said shafts; a series of fingers mounted directly on the other shaft and moved by the rotation thereof; a thumb pivoted to said body portion; and means for

moving said thumb in unison with said fingers.

12. In an artificial hand, the combination of a hollow body portion; a pair of parallel shafts journaled therein; means for positively driving one of said shafts; gear connections between said shafts; a series of fingers mounted directly on the other shaft and moved by the rotation thereof; a thumb pivoted to said body portion; and connections between said thumb and the index finger for moving the former in unison with the latter.

13. In an artificial hand, the combination of a body portion; a series of fingers pivotally connected thereto; a shaft mounted in said body portion; connections between said shaft and said fingers for moving the latter; an operating shaft mounted in said body portion; gear connections between said shafts; a member secured to the operating shaft; and a toothed member movable into position to engage the first-named member for locking said operating shaft against rotation.

14. In an artificial hand, the combination of a body portion; a series of fingers pivotally connected thereto; a shaft mounted in said body portion; connections between said shaft and said fingers for moving the latter; an operating shaft mounted in said body portion; gear connections between said shafts; a member secured to the operating shaft; and a spring-controlled retaining member movable into position to engage the first-named member for locking said operating shaft against rotation.

15. In an artificial hand, the combination of a body portion; a series of fingers pivotally connected thereto; a shaft mounted in said body portion; connections between said shaft and said fingers for moving the latter; a sleeve; a wrist-plate interposed between said sleeve and body portion and connected to the former, said wrist-plate having a pair of openings formed therein and said body portion being formed with a pair of slots registering with said openings; an operating shaft journaled in said body portion; connections between said operating shaft and the first-named shaft; and a rocker secured to said operating shaft and provided with a pair of rods projecting through said slots into said openings.

16. In an artificial hand, the combination of a body portion; a series of fingers piv-

otally connected thereto; a sleeve; a wrist-plate interposed between said sleeve and body portion and rigidly connected to the former; an operating shaft mounted in said body portion; connections between said shaft and said fingers for moving said fingers when said shaft is turned; and a rocker secured to said shaft and provided with a pair of rods engaged with said wrist-plate.

17. In an artificial hand, the combination of a body portion; a series of fingers pivotally connected thereto; an operating shaft mounted in said body portion; connections between said shaft and said fingers for operating the latter from the former; a member secured to said shaft; and a spring-controlled member arranged to engage the first-named member for holding said shaft against rotation.

18. In an artificial hand, the combination of a body portion; a series of fingers pivotally connected thereto; an operating shaft mounted in said body portion; connections between said shaft and said fingers for operating the latter from the former; a sleeve; a wrist-plate interposed between said body portion and said sleeve; a member secured to said shaft and provided with a pair of rods engaged with said wrist-plate, said body portion being formed with a pair of slots wherein said rods are laterally movable, to permit lateral movement of said body portion relative to said wrist-plate; and means arranged to engage said member for locking the same against movement.

19. In an artificial hand, the combination of a body portion having its palm provided with a gripping pad; a series of fingers pivoted to said body portion; and means for flexing said fingers.

20. In an artificial hand, the combination of a body portion; a plurality of jointed digits pivotally connected thereto, each joint of each digit having an annular friction band fitted thereon; and means for flexing said digits.

In testimony whereof we have hereunto set our hands in presence of two subscribing witnesses.

JOUEL M. SHACKELFORD.
TRUMAN ALEXANDER.
